(57) **CLAIM**

The ornamental design for the bathroom/area rug, as shown and described.

DESCRIPTION

FIG. 1 is a left perspective view of the rug showing the design as applied to the perimeter (convexed and concaved sculpting of the outer edges) of the bathroom/area rug. FIG. 2 is a left perspective view of the rug as it relates to the open space near a bathtub in a bathroom. (The bathtub can be substituted by a sofa or any open space.); and, FIG. 3 is a top plan view of the rug embodying my new invention (design).

The backside of the rug is flat.

The pattern, which is partially shown for ease of illustration, represents a conventional fabric and is understood to repeat uniformly throughout the indicated area.

The broken line showing is for illustrative purposes only and forms no part of the claimed design.
